HAT CONE

Harry A. Berger, New York, N. Y.

Application October 15, 1931, Serial No. 569,091

1 Claim. (Cl. 211—33)

This invention relates to a hat cone and has for an object to provide an improved cone for hats which is adjustable for different sizes.

A further object of this invention is to provide a hat cone which will hold a number of different sized hats without the necessity of changing the adjustment thereon.

Yet a further object of this invention is to provide a hat cone which is collapsible to a flat position when not in use and may be quickly and easily assembled into operative position.

A further object of this invention is to provide a hat cone which is frustro-conical when in operative position and flat when in inoperative position, and which when in operative position each adjustment provides for the placing thereon of a new combination of many hats of different sizes, due to the frustro-conical structure of the cone.

Another object of this invention is to provide a hat cone which protects the hats, when placed thereon, from being crushed while being shipped or delivered or when placed in a suit case or trunk.

One of the features of this invention is to provide a hat stand for use in the home, store or similar place.

Another feature of this invention is that the outside portion of the hat cone may be utilized as an advertising medium.

A still further object of this invention is that the conical shape of this device, when properly adjusted, prevents the edge or brim of a hat from contacting with the support or base upon which the cone is placed, thereby likewise preventing the edge or the brim of a hat from touching said support or base and further thereby preventing the soiling or crushing of said edge or brim of a hat.

With the foregoing and other objects in view, as will hereinafter become apparent, this invention comprises the constructions, combinations, and arrangements of parts, hereinafter set forth, claimed and shown on the accompanying drawing. In the drawing,

Figure 1 is a perspective view of the hat cone in assembled or operative position, a hat being shown thereon in dotted outline.

Figure 2 is a side plan view of the cone in operative position.

Figure 3 is a top plan view of Figure 2, a different head size hat being shown in dotted outline.

Figure 4 is a plan view of the cone in unassembled position.

Figure 5 is a detail plan view of the tongue and slot connections, and,

Figure 6 is an edge view of Figure 5.

There is shown at 10 the assembled hat cone having a hat shown in dotted outline at 11 thereon, a different size hat being shown at 12. This hat cone 10 is formed of a piece of sheet material preferably card board, cut out as shown in plan view in Figure 4 at 14, the shape being substantially that of the development of the side of the frustum of a cone.

There is formed at one end of this material 14 a tongue 15 cut in as at 16, while at the other end 17 of this sheet material 14 are a plurality of cooperating slots 18, 19, 20 and 21. Although only four slots are shown, it will be obvious that a greater or lesser number of slots may be provided. Each of these slots may have a size indication 22 printed adjacent thereto while advertising matter may be printed on the face of member 14. When shipping or storing these display cones they are placed in the position shown at 14 in Figure 4 and require only a minimum amount of space. When it is desired to make use of the same, the tongue 15 is inserted in any one of the slots 18, 19, 20 or 21, as desired. The hat 11 or 12 is then placed thereover and it is thus in a convenient position for use.

As will be observed, different size hats may be placed on this cone 10 when in the same adjustment, but when desired the cone 10 may be adjusted to a different size by using a different one of the slots 18, 19, etc. and thus be suitable for another range of sizes of hats.

With this form of hat cone it will be observed that only one size cone need be formed for practically any size of hat, for the same cone would hold a range of sizes in one adjustment and by changing the adjustment may hold a further range of sizes, thus eliminating the necessity for providing different size cones.

The novel features and the operation of this device will be apparent from the foregoing description. While the device has been shown and the structure described in detail, it is obvious that this is not to be considered limited to the exact form disclosed and that changes may be made therein within the scope of what is claimed without departing from the spirit of the invention.

Having thus set forth and disclosed the nature of this invention, what is claimed is:

An adjustable hat displaying and supporting cone comprising an elongated sheet of material having parallel arcuate sides, said sheet constituting the development of the frustum of a cone

and having a series of spaced parallel slits formed intermediate the arcuate sides adjacent an end thereof, the opposed end having a slit formed therein inwardly from the edge also intermediate the arcuate sides to produce a tongue, said tongue cooperating with the series of slits for forming cones of various sizes whereby there may be supported a plurality of different hat sizes within a

limited range, the supported hat being adapted to frictionally engage the sides of the cone at a height above the bottom of the cone determined by the size of the hat, each differently sized cone formed having a different range of hat sizes it may support. 5

HARRY A. BERGER.
